MARKING MACHINE HAVING ADJUSTABLE
PARALLEL COMPRESSIBLE FEED ROLLS
AND A CONDUIT EXTENDING UPWARDLY
FROM SAID ROLLSHarold L. Lewis, Indianapolis, Ind., assignor to
J. D. Adams Manufacturing Company, Indianapolis, Ind., a corporation of Indiana

Application October 5, 1943, Serial No. 504,999

4 Claims. (Cl. 222—238)

1

It has heretofore been proposed to increase the night-time visibility of painted stripes on roads, air-field runways, and other surfaces by embedding in the painted stripe glass beads or other light-reflective particles. My invention relates to a machine for applying such beads or other particles to the paint-stripe, and has for its primary object the production of a machine which will provide an even distribution of beads or other particles irrespective of the speed at which the machine moves along the paint-stripe. Another object of my invention is to produce a machine that will be durable and resistant to wear of a type which would effect variations in the rate of bead-discharge. A further object of my invention is to produce a machine which will not be adversely affected by the passage of irregular or over-sized particles through it. Still another object of my invention is to provide means whereby the machine may be adapted to deposit beads or other particles on paint-stripes of any width.

In carrying out my invention in the form herein illustrated, I mount the bead-dispensing means on the same vehicle which carries the stripe-painting mechanism, arranging it in rear of the paint-applicator so that the beads discharged by it will fall on the paint stripe. The dispenser comprises a housing within which are located two rotatable rolls arranged on parallel axes in a horizontal plane. These rolls are faced with rubber or other compressible material and are held in contact with each other. One of the two rolls is power-driven, and rotates the other by reason of its engagement therewith, in a direction such that the contacting portions of the roll faces move in a generally downward direction; and the beads or other light-reflective material which the device is to dispense are supplied to the rolls from above so that they will pass downward therebetween as the rolls rotate. To control the width of the stream of beads discharged from the dispenser, I may mount in the housing a removable member having a slot of appropriate width through which the beads are fed to the rolls. Since beads will be dispensed only when the vehicle is in motion, the dispenser may be driven from one of the vehicle wheels. Desirably, joint control means are provided for the dispenser and the paint-applying mechanism. To control the density of bead-distribution, the dispenser may be driven through a variable speed drive.

The accompanying drawings illustrate my invention: Fig. 1, is a side elevation of a ve-

hicle carrying both paint-applying means to form the desired stripe and a bead-dispenser to deposit beads on that stripe, parts of the structure being broken away; Fig. 2 is a fragmental vertical section on the line 2—2 of Fig. 1; Fig. 3 is a plan view of the bead-dispenser with portions thereof broken away and shown in section; Fig. 4 is an end elevation of the bead dispenser with portions of the dispenser-housing broken away; and Fig. 5 is a plan view of the clutch and clutch-operating mechanism by means of which the dispenser is controlled.

The vehicle illustrated in the drawings comprises a frame 10 carried on front and rear ground-supported wheels 11 and 12. From the frame 10 both the paint-applying and the bead-dispensing mechanism are supported. The paint-applying mechanism may take any desired form. That shown in the drawing is one more fully described in my co-pending application Serial No. 466,578, filed November 23, 1942, now Patent No. 2,401,431, dated June 4, 1946, and includes a jet-forming nozzle 13 supplied with paint under pressure through a hose 14 from a drum 15 and with air through a hose 16 from a blower (not shown).

The bead-dispenser, which is designated in its entirety by the reference numeral 18, is supported on the frame 10 in rear of the nozzle 13. Conveniently, the dispenser comprises a housing 20 provided with removable end walls 21. The housing has a bead-receiving opening 22 in its upper side and a downwardly directed bead-discharging opening 23 in its lower side. The bead-receiving opening 22 is connected, as through a hose 24, with a hopper 25 which is mounted on the vehicle frame and which carries a supply of beads.

To support the dispenser 18 in the device shown in the drawings, I may employ brackets 30 and 31 which are attached respectively to the side members of the frame 10, as will be clear from Fig. 2. The lower ends of these brackets support a pair of parallel, horizontal rods 32 which are received in openings in ears 33 projecting laterally from the end walls 21 of the dispenser housing.

Within the dispenser housing 20 are two rolls 35 and 36 arranged on parallel axes in a common horizontal plane. The roll 35, which is power-driven, is rigid with a shaft 37 which is journaled in bearings 38 in the end walls 21 of the dispenser housing. The other roll 36 is rotatably mounted on a stationary shaft 39. For a purpose which will hereinafter be made ap-

parent, the shaft 39 has co-axial eccentric end portions 40 rotatably received in alined openings in the end walls 21, so that by rotating the shaft 39 about the common axis of its eccentric end portions 40 the distance between the two rolls 35 and 36 can be varied. A set-screw 41, mounted in one of the end plates 21 in position to bear against the associated shaft-end 40, holds the shaft 39 in any desired position of angular adjustment. The rolls 35 and 36 are formed of, or at least faced with, some suitable compressible material, such as soft rubber.

To control the width of the stream of beads discharged from the dispenser 18, I employ a guide member 45 which is supported within the housing 29 above the rolls 35 and 36. The upper end of the member 45 fills the opening 22, and the member is provided with an elongated slot 47 which extends downwardly through it. The lower end of the member 45 is shaped to conform to the surfaces of the rolls 35 and 36; but in order to prevent wear of the rolls, the member 45 is desirably supported with its lower end spaced from the rolls by a distance slight enough to prevent escape of the beads from the slot 47 otherwise than downwardly between the rolls. Accordingly, the length of the slot 47 will determine the width of the stream of beads discharged from the discharge opening of the dispenser-housing.

For the purpose of driving the shaft 37 and the roll 35 rigid therewith, the shaft 37 projects outwardly through the outer end wall of the dispenser housing, where there is keyed to it a V-belt pulley comprising, in the preferred structure, two members 50 and 51. The belt pulley 50-51 is operatively connected by a V-belt 52 with a second pulley which, in the preferred structure, consists of two members 53 and 54 and which is rotatable with a shaft 56 supported in fixed axial position on a bearing 57 on the bracket 30.

As previously indicated, the dispenser 18 is conveniently driven from one of the wheels by which the vehicle is supported. As will be clear from the drawings, especially Fig. 2, the rear wheels 12 of the vehicle are mounted on a live axle 60, and attached to such axle is a driving sprocket 57 operatively connected by a chain 58 with a driven sprocket 59 rigid with a shaft 64 which is rotatably supported in fixed axial position in a suitable bearing 65 forming part of the bracket 30. The two bearings 57 and 65 are so arranged that the shafts 56 and 64, which they respectively support, are in alinement with each other with their adjacent ends in opposed relation. The adjacent ends of the two shafts 56 and 64 support two co-operating jaw-clutch members 67 and 68, the former fixed on the shaft 56 and the latter rotatable with but slidably axially on the shaft 64 to permit its engagement with and disengagement from the other clutch member 67.

Desirably, the driving mechanism for the dispensing device 18, whatever form it takes, includes means by which the speed of operation of the dispensing device can be varied relative to the speed of the vehicle in order to control as desired the density of bead-distribution on the paint-stripe formed by the nozzle 13. In the device shown in the drawings, variation in the speed of the dispenser 18 is attained by varying in opposite senses the effective diameters of the two pulleys 50-51 and 53-54 which co-operate with the belt 52. As will be clear from Fig. 5, the member 53 of the driving pulley is rigid with the shaft 56, while the other pulley-member 54 is screw-

threadedly mounted on the end of the shaft 56 so that its axial position relative to the member 53 may be varied. A lock unit nut 70, also mounted on the screw-threaded end of the shaft 56, serves to hold the adjustable pulley-member 54 in any desired position of adjustment. In the driven pulley 50-51, the member 50 is rigid with the shaft 37 and the member 51, while keyed to such shaft to rotate therewith, is axially movable thereon. A compression spring 71, acting between the pulley-member 51 and a fixed abutment 72 on the shaft 37, forces the pulley-member 51 toward the member 50.

To increase the density of bead-distribution on the paint-stripe, the speed of the dispenser 18 relative of the speed of the vehicle will be increased. To effect this result, the nut 70 is loosened, and the pulley-member 54 is rotated on the screw-threaded end of the shaft 56 to bring it closer to the member 53 and thus increase the effective size of the driving pulley. When the desired position of adjustment of the member 54 is obtained, the lock-nut 70 is again tightened. Because the belt 52 has a fixed length, the increase in diameter of the pulley 53-54 will necessitate a decrease in the effective diameter of the driven pulley 50-51, and this decrease is effected by movement of the member 51 outwardly against the force exerted upon it by the spring 71.

As previously indicated, I find it desirable to control the paint-applying mechanism and the bead-dispenser jointly. In the paint-applying mechanism shown in the drawings and more fully described in my co-pending application above referred to, the flow of paint through the hose 14 to the nozzle 13 is controlled by a valve operated by pressure-responsive mechanism including a pressure cylinder 75. Compressed air supplied to the cylinder 75 through a conduit 76 under control of a manually operated pilot valve 77 serves to open the paint-supply valve.

To provide joint control of the paint-applicator 13 and the bead-dispenser 18, control of the latter is effected by air under pressure supplied through a branch 78 of the conduit 76. To this end, the movable clutch member 68 is associated with a shifter-fork 80 mounted on a piston rod 81. The piston rod 81 extends into a fluid-pressure cylinder 82 where it is provided with a piston 83. A spring 84, conveniently arranged within the cylinder 82, biases the rod 81 for movement in a direction which will effect disengagement of the clutch member 68 from the clutch member 57, and the piston 83 is movable in the opposite direction by compressed air supplied to the cylinder 82 through the branch-conduit 78.

When, with the vehicle in motion, it is desired to begin the application of the paint-stripe, the pilot valve 77 is opened, thus supplying air under pressure to the cylinders 75 and 82. The air supplied to the cylinder 75 opens the paint-control valve and causes paint to be discharged downwardly from the applicator 13. Air supplied to the cylinder 82, forces the piston 83 and piston rod 81 outwardly to cause engagement of the clutch member 68 with the clutch member 57, after which the bead-dispenser 18 will begin to operate to discharge a stream of beads. Because the bead-dispenser is located some distance in rear of the paint-applicator 13, beads would fall on an unpainted surface if the bead dispenser and paint applicator were thrown into operation simultaneously. To avoid this, I may delay the action of the pressure-responsive mechanism which operates the clutch-member 68, as by placing in the conduit 78 a valve 85. By proper ad-

justment of this valve, engagement of the clutch member 68 with the clutch member 67, and consequent operation of the bead-dispenser 18, may be delayed for an interval after the paint-applicator 13 has been thrown into operation; and the extent of this interval can be varied in co-ordination with the speed of the vehicle so that operation of the bead-dispenser 18 will begin as it reaches the beginning of the paint-stripe formed by the applicator 13. If it is desired to obtain a paint-stripe without beads, the valve 85 may be closed entirely.

In the machine shown, the cylinders 75 and 82 exhaust through a port 77 in the valve 77 when the latter is moved to throw the painting means and dispenser out of operation. Air thus exhausted from the cylinder 82 has to pass the valve 85 which therefore operates to delay the cessation of dispenser-operation as well as to delay the institution of dispenser operation in the manner above set forth. Thus, if the vehicle continues to move after the paint nozzle 13 has been shut off the dispersing of beads will continue for an interval as the vehicle moves toward or to the end of the painted stripe.

In operating the machine, the vehicle is put in motion in line with the stripe which is to be formed; and at the point where the stripe is to start, the valve 77 is opened, throwing into operation first the paint-applicator 13 and subsequently the bead-dispenser 18 in the manner above described. As the vehicle progresses over the surface to be painted, paint from the applicator 13 forms a stripe upon which beads from the dispenser 18 fall to become embedded in the still wet paint. The width of the stream of beads discharged from the dispenser will be substantially equal to the length of the slot 47 in the member 45; and by using a member with a slot of appropriate length, the width of the bead-stream may be made equal to that of the stripe formed by the applicator 13.

The beads supplied to the rolls 35 and 36 through the slot 47 in the member 45 become embedded in the compressible surface portions of the rolls as they pass therebetween, and the rolls operate to discharge a substantially uniform quantity of beads at each revolution. Minor variations in the quantity of beads discharged at each revolution of the rolls 35 and 36 can be effected by varying the distance between the axes of the rolls, as by rotating the shaft 39 about the common axis of its eccentric end portions 40; but the extent of variation in the rate of bead discharge obtainable in this manner is relatively limited. Accordingly, the rotatability of the shaft 39 about its eccentric end portions is employed primarily for the purpose of relieving pressure between the rolls when the device is not in operation; and variation in the density of bead distribution on the paint-stripe will usually be obtained through appropriate adjustment of the drive-pulley 53—54. For any setting of the pulley 53—54, there will be a definite ratio between the speed of the axle 60 and the speed of the rolls 35 and 36; and, since the rolls 35 and 36 operate to discharge a constant quantity of beads at each revolution, the density of bead-distribution on the paint-stripe will remain substantially constant irrespective of any variation in the speed of the vehicle.

Throughout the above description I have referred to my device as a bead-dispenser, but it is to be understood that it can be employed to distribute light-reflective particles, whether trans-

parent or opaque, of shapes other than spheroidal. As long as the particles supplied to the device are of approximately uniform size, the rolls will operate to discharge a substantially constant quantity of them at each revolution; and even if the particles vary in size, the larger particles will not be retained in the device where they might interfere with uniformity of delivery but will be discharged with the smaller particles by passing downwardly between the rolls without injuring the compressible surface portions thereof. To obtain beneficial results with my invention, it is not essential that both of the rolls 35 and 36 have compressible surface portions. It is not necessary that one roll be driven solely as the result of its contact with the other or that the dispenser be mounted on the same vehicle with the stripe-painting apparatus.

I claim as my invention:

1. In a device for distributing light-reflective particles upon a painted surface, a hollow casing having particle-receiving and particle-discharge openings, in its upper and lower walls respectively, a pair of feed rolls rotatably mounted within said casing on parallel axes located in a common, substantially horizontal plane, said rolls having interengaging surfaces, a member disposed above said rolls and having a vertical slot extending through it and terminating between said rolls, said slot having a predetermined length in a direction parallel to the roll-axes and constituting the sole path over which particles entering said casing can reach said rolls, said member being removable from said casing, and means for rotating said rolls in such a direction that their interengaging surface portions move downwardly, whereby light-reflective particles supplied to the rolls through said slot will be fed downwardly between the rolls and discharged through said discharge opening.

2. In a device for distributing light-reflective particles upon a painted surface, a pair of feed rolls, supports rotatably supporting said feed rolls on parallel axes in a substantially horizontal plane, said rolls having interengaging surfaces of compressible material, means for varying the distance between said supports whereby to vary the distance between the roll-axes and the area of the interengaging portions of the roll-surfaces, means for rotating said rolls in such a direction that their interengaging surface portions move downwardly, and means for feeding light-reflective particles to said rolls, said means comprising a conduit extending upwardly from the interengaging portions of the rolls and having a lower end lying close to and effectively closed by said rolls.

3. In a device for distributing light-reflective particles upon a painted surface, a pair of feed rolls, supports rotatably supporting said feed rolls on parallel axes in a substantially horizontal plane, said rolls having interengaging surfaces at least one of which is of compressible material, means for varying the distance between said supports whereby to vary the distance between the roll-axes and the area of the interengaging portions of the roll-surfaces, means for rotating said rolls in a direction such that their interengaging surface portions move downwardly, and means for feeding light-reflective particles to said rolls, said means comprising a conduit extending upwardly from the interengaging portions of the rolls and having a lower end lying close to and effectively closed by said rolls.

4. The invention set forth in claim 3 with the

addition that said roll-rotating means is directly connected to but one of said rolls, the other roll being driven by reason of the interengagement of the rolls.

HAROLD L. LEWIS. 5
